[57] CLAIM

The ornamental design for a cuticle treatment kit, as shown and described.

DESCRIPTION

FIG. 1 is a top plan view of a cuticle treatment kit showing my new design with the cover member fragmented for clarity of illustration;

FIG. 2 is a side elevational view thereof; and

FIG. 3 is an exploded top-side perspective view thereof. The undisclosed base portion is plain and unornamented.

FIG. 1

FIG. 2

FIG. 3
